UNITED STATES PATENT OFFICE.

WILLIAM N. COSGROVE, OF FARIBAULT, MINNESOTA.

GRINDING-MILL.

SPECIFICATION forming part of Letters Patent No. 242,756, dated June 14, 1881.

Application filed February 12, 1880.

To all whom it may concern:

Be it known that I, WILLIAM N. COSGROVE, of Faribault, in the county of Rice and State of Minnesota, have invented certain new and useful Improvements in Grinding-Mills; and I do hereby declare the following to be a full, clear, and exact description of the same, reference being had to the accompanying drawings, forming part of this specification, in which—
10 Figure 1 is an end view of the mill; Fig. 2, a vertical section taken on the line xx ; Fig. 3; and Figs. 3 and 4, side and top views, respectively, with part of the casing thrown open.

Similar letters of reference in the several figures denote the same parts.

This invention relates to certain novel improvements in vertical grinding-mills, which will be hereinafter fully described, and pointed out in the claims.

20 In the drawings, A represents the casing of the mill, B the large grinding-roll, and C C' C² C³ the small grinding-rolls, arranged around the periphery of the roll B. The small rolls are located at sufficient distances apart to accommodate screen-sections D D' D², of wire or bolting cloth, between them, as shown in Fig. 2. The journals of the small rolls are mounted in boxes or bearings that are capable of being independently adjusted back and forth 25 in radial guides a a by means of screw-rods f and hand-wheels h' . This arrangement enables the small rolls to be independently adjusted nearer to or farther from the large roll B at pleasure. The journals of the large roll 30 are also mounted in movable bearings or boxes, and by means of screw-rods i and hand-wheels k can be adjusted with respect to the small rolls. The small rolls and the large roll rotate toward each other, and motion is preferably 35 imparted to them by means of a large pulley, F, on one end of the journal of the large roll, driven from any prime mover, a second pulley, G, on the other end of the journal of said large roll, pulleys H H' H² H³ on the journals of the 40 small rolls, an idle-pulley, T, and a connecting-belt, I, applied as shown in Fig. 1.

In order that the material passed between the small rolls and the large roll may be subjected to a grinding or rubbing action, instead of being 45 nearly crushed, the said rolls are so proportioned and geared that their peripheries travel at different rates of speed.

The screen-sections D D' D² are held in frame K K' K², secured to the sides of the casing, and below each screen-section and over 55 the top of the rolls C' C² C³ are placed guard-plates L' L² L³, upon which the flour and middlings screened out through the screens fall, and are conducted into the chambers M M' M² M³. Within the chambers M M' M² M³ are located air-trunks N N' N², &c., connected by 60 air-tubes n n' n² to a common tube, O. A suction-fan or other means for producing a suction is applied to the outer end of the tube O, and strong currents are thereby induced in the 65 chambers M M' M² M³, causing a draft through the screens sufficient to draw off the fine flour or middlings as fast as made. That the flour and middlings thus passed through the screens may not be carried off through the air-trunks 70 by the suction, said air-trunks are covered with cloth or some other fibrous material which will admit of the passage of air but not permit any flour to go through. The flour and middlings pass out of the compartments through 75 openings R in the outer casing, and are thence conveyed to the proper bolts and purifiers. If desired, the flour and middlings from each screen may be kept apart from the rest and 80 conveyed to different bolts and purifiers and separately treated.

Both the large grinding-roll B and the small grinding-rolls C C' C² C³ are provided on their peripheries with grooves h , arranged spirally after the manner of screw-threads, each groove 85 extending around several times. The grooves h on the large roll B have a shearing action from right to left, while the grooves on the co-operating small rolls C C' C² C³ have preferably a shearing action from left to right, the 90 tendency of one set of grooves being to carry the material being ground in one direction, and the tendency of the other set being to carry it in the opposite direction. Each roll is also further provided with other grooves, g , running parallel, or nearly so, with its axis of rotation, the operation of said grooves being to subject the material to a shearing action transversely of the rolls in addition to the oblique shearing action of the spiral grooves h , thus 95 rendering the rolls doubly effective.

The operation of the mill is as follows: The grain, being fed from the hopper, is subjected to the action of the first small roll, C, and the

large roll B, and the resulting fine flour and middlings are as fast as made drawn off through the screen D by the suction produced, as before described. The remaining material then 5 passes between the second roll, C', and the roll B, which are adjusted slightly nearer together, when it is further reduced and the resulting fine flour and middlings carried out through the screen-section D', and so on throughout the 10 mill, the material being subjected to alternate reductions and screenings until all the flour and middlings have been eliminated. The flour and middlings screened out pass into the chambers behind the screens, and thence out of the mill, 15 after which they are conveyed to the proper bolts or purifiers, as before described.

I claim as my invention—

1. In a grinding-mill, the combination of a large grinding cylinder or roll, a series of small 20 grinding-rolls arranged around the grinding-periphery of the large roll and adapted to be adjusted nearer to or farther from the same, whereby to gradually reduce the material to a greater degree of fineness, and screens or screen-sections 25 between the small rolls for screening out the fine flour and middlings resulting from each reduction, substantially as described.

2. In a grinding-mill, the combination of a large grinding cylinder or roll, a series of small 30 grinding-rolls arranged around the grinding-periphery of the large roll and adapted to be adjusted nearer to or farther from the same, whereby to gradually reduce the material to a greater degree of fineness, screens or screen-

sections between the small rolls for screening 35 out the fine flour and middlings, and a suction or suctions behind the screen-sections for assisting in screening out the fine flour and middlings as fast as made, substantially as described.

3. In a grinding-mill, the combination of the large grinding cylinder or roll, the series of small rolls, the screen-sections between the small rolls, the chambers M M' M² M³, provided 40 with the air-trunks N N' N², covered with cloth 45 or other fibrous material, and an exhaust applied to the said air-trunks, substantially as described, for the purpose specified.

4. The combination, with the large grinding cylinder or roll, the series of small grinding-rolls co-operating therewith, and the screens 50 between the small rolls, of the chambers M M' M² M³, arranged behind the screens and containing the cloth-covered air-trunks, and having 55 openings for the escape of the flour and middlings, substantially as described.

5. In a grinding-mill, a grinding-roll having 60 peripheral grooves running substantially parallel to its axis of rotation, and also having other grooves running spirally around it, in combination with a co-operating roll similarly grooved, but adapted to revolve in an opposite direction, substantially as described, for the purpose specified.

WILLIAM N. COSGROVE.
